UNITED STATES PATENT OFFICE.

CHARLES R. HAZEL, OF CHARLEROI, PENNSYLVANIA

CASTING AND ANNEALING TABLE.

1,168,303.

Specification of Letters Patent. Patented Jan. 18, 1916.

Application filed May 22, 1914. Serial No. 840,336.

To all whom it may concern:

Be it known that I, CHARLES R. HAZEL, a citizen of the United States, residing at Charleroi, in the county of Washington and State of Pennsylvania, have invented certain new and useful Improvements in Casting and Annealing Tables, of which the following is a specification.

This invention relates to a table for annealing a sheet of plate glass and the principal object of the invention is to provide the table with improved means for heating the stationary and movable sections of the table and for permitting the sections to gradually cool while the plate of glass is cooling and being pressed.

Another object of the invention is to so construct the table that the movable section may be held out of a position to compress the sheet of glass while the glass is being rolled and then move to a position to compress the sheet of glass after it has been rolled.

Another object of the invention is to provide an improved water circulating system for the movable and stationary sections.

Another object of the invention is to provide the stationary and movable sections with means for permitting the sections to be heated by an electrically operated system.

This invention is illustrated in the accompanying drawings, wherein—

Figure 1 is a side elevation of the improved table; Fig. 2 is a top plan view of the improved table; Fig. 3 is an enlarged fragmentary elevational view of the improved table; Fig. 4 is a fragmentary transverse sectional view through the table taken along the line 4—4 of Fig. 2; Fig. 5 is a fragmentary sectional view through the stationary section taken along the line 5—5 of Fig. 1; Fig. 6 is a sectional view taken along the line 6—6 of Fig. 5; Fig. 7 is a view similar to Fig. 5 taken along the line 7—7 of Fig. 1; and Fig. 8 is a view similar to Fig. 6 taken along the line 8—8 of Fig. 7.

The table is provided with a base or foundation composed of supports 10 which carry the rails 11, the rails being secured to the supports 10 and being braced by the braces 12. The treads 13 of the rails 11 are secured to the rails by any suitable means and are of such width that they may fit into the grooves of the wheels 14 rotatably supported by the bearing brackets 15 of the movable section 16. The bracket of this table is built

over a pit so that the water pipes may move downwardly as the movable section moves over the stationary section 17 which is rigidly connected with the track.

The stationary section is formed from a plurality of metallic bars 18 the contacting edges of which are provided with grooves in which keys 19 fit as shown in Figs. 5 and 7. These bars are also provided with transversely extending ribs 20 provided with undercut grooves 21 to receive the dovetailed ribs 22 of the supporting bars 23. The bars are also provided with transversely extending sleeves 24 through which the securing bolts 25 pass to securely hold the bars 18 together. Spacing strips 26 are carried by the side bars 18 of the stationary section to regulate the thickness of the glass and prevent the soft glass from being compressed beyond a desired amount. These strips may be removed and replaced by others so that glass of different thickness may be formed. In order to permit the water pipes 27 and wires 28 to pass through the bars 18 there is provided a plurality of passageways 29 which extend the full length of the bars thus permitting the ends of the water pipes to extend beyond the ends of the stationary section as shown in Fig. 1. These pipes 27 are connected with the cross heads 30 and 31 which in turn communicate with the pipes 32 and 33 respectively. These pipes 32 and 33 lead from the inlet and outlet mains from which the pivoted pipes 34 lead, the pipes 34 being pivoted so that when the movable section moves longitudinally upon the rails 11 the end sections 34 may move to permit of the sliding movement of the movable section.

The movable section comprises a plurality of longitudinally extending bars 35 which are provided with side grooves in which the keys 36 fit and are also provided with transversely extending sleeves 37 to receive the securing screws 38 and with longitudinally extending passageways through which the water pipes 39 pass. Wires 40 pass through the passageways through which pipes 39 pass so that the bars of the movable section may be heated in the same manner that the bars of the stationary section are heated. In order to support the bars 35 there are provided trusses 41 which extend through under cut slots formed transversely in the bars 35 and have their outer ends connected with the brackets 15 which carry the

supporting wheels 14. The webs 42 of the trusses 41 are provided with cut outs through which the pipe 43 passes, the forward end of the pipe 43 being connected with the cross head 44. This cross head 44 is connected with the pipes 39 by the nipples or branches 45 and has one end portion 46 bent to permit the cross head 44 to communicate with the interior of the hollow roller 47. This roller 16 47 is rotatably mounted by means of brackets 48 and rests upon the spacing strips 26 while the movable section is moving across the stationary section. A pipe 49 leads from the opposite end of the roller 47 and is connected 15 with a cross head 50 with which the pipes 39 are connected as shown in Figs. 1 and 2. Pipes 51 and 52 lead from the pipe 43 and cross head 50 respectively and telescope in the pivotally mounted sections 34 of pipes 32 20 and 33 so that when the movable section moves longitudinally the pipes 51 and 52 may slide in the sections 34 of pipes 32 and 33 and move pivotally with respect to pipe 43 and cross head 50 and thus not interfere 25 with the sliding movement of movable section 16.

In the operation of this device the melted glass is placed upon the stationary section, the current having been first turned on so 30 that it may pass through the wires to heat the water in the pipes and heat the sections and the movable section is then moved across the stationary section so that the roller which rests upon the strips 26 will roll the 35 glass into a plate. The treads 13 of the rails 11 are provided with cut outs 53 so that when the roller has passed over the stationary section the supporting wheels may move into these depressions thus permitting the 40 movable section to drop upon the strips 26 and compress the glass to expel all of the air from the glass. After the movable section has dropped upon the strips 26 the electric current is cut off and the water in the pipes 45 will then gradually cool and as it cools take up the heat from the bars forming the two sections thus causing the sections to gradually cool and cause the plate of glass to be properly annealed. After the plate of glass 50 has cooled the movable section is returned to the position shown in Fig. 1 and the table is then ready for forming a new plate of glass. The glass can therefore be rolled into a plate 55 by the roller 47 and the rolled glass then compressed while still hot and then gradually cooled, the cooling while under compression causing all of the air to be expelled from the glass and the glass properly annealed.

60 What is claimed is:—

1. An annealing table comprising a track, a stationary table carried by said track, a movable table mounted upon said track for moving across said stationary table, spacing 65 strips carried by said stationary table, a

roller carried by said movable table and engaging said spacing strips while said movable table is moving across said stationary table, the rails of said track being provided with depressions into which the wheels of 70 said movable table pass when said movable table is above said stationary table to permit said movable table to drop upon said spacing strips, a water circulating system for said tables and roller, and means for heating 75 said tables.

2. An annealing and casting table comprising a track, a stationary table carried by said track, a movable table having its supporting wheels resting upon the rails of said track, said tracks being formed to permit said movable table to move to a lowered position when above said stationary table and rest upon said stationary table, a spreading element carried by said movable table for spreading material upon said stationary table, a water circulating system for said tables and spreading element, and means carried by said table for heating the water in the water circulating system to heat said 90 table.

3. A casting and annealing table comprising a track, a stationary table carried by said track, a movable table mounted upon the rails of said track, a spreading element carried by said movable table for spreading material upon said stationary table while said movable table is moving above the same, means for permitting said movable table to rest upon said stationary table after moving above the same, a water circulating system for said tables and spreading element, and a heating system for said tables. 95

4. In a casting and annealing table a stationary table, a movable table, a spreading element carried by said movable table, a water circulating system for said table and spreading element comprising an inlet main, pipes passing through said stationary table, a cross head connecting the pipes at one end of said stationary table, a pipe connecting said inlet main with said cross head, a second cross head connected with the pipes at the opposite ends of said stationary table, a pipe connecting said outlet main with said second cross head, pipes passing through said movable table, a cross head connected with the pipes at one end of said movable table, a cross head connected with the opposite end of said movable table, a pipe connecting the second cross head of said movable table with said spreading element, a pipe leading from said spreading element to the first mentioned cross head of said movable table, a pipe leading from the second mentioned cross head of said movable table above the same, a pipe having a pivotal connection with said outlet main, a pipe connected with the pipe leading from the said second mentioned cross head to said 120 125 130

movable table and having a telescoping connection with said last mentioned pipe, a pipe having a pivotal connection with said inlet main, and a pipe leading from the first mentioned cross head to said movable table and having a telescoping connection with said last mentioned pipe, and a heating system for said tables.

5. In a casting and annealing table, a support, a stationary table carried by said support, a movable table mounted upon said support, a roller carried by said movable table, said tables each comprising a plurality of longitudinally extending bars provided with passageways, the contacting edges of said bars being provided with grooves forming keyways, keys extending through said keyways to prevent independent vertical movement of said bars, said bars being also provided with transversely extending under cut grooves, cross bars extending transversely across said longitudinally extending bars and provided with dovetailed ribs fitting into the under cut grooves of said bars, fastening means extending transversely through said bars, a water circulating system including pipes passing through the longitudinally extending passageways of said bars, and electric conductors passing through said longitudinally extending passageways adjacent said pipes for heating the water in said pipes.

6. In a casting and annealing table a support, a stationary table carried by said support, a movable table mounted upon said support, a spreading roller carried by said movable table, said roller resting upon said stationary table while said movable table is moving across the same and said movable table resting upon said stationary table after reaching a position above the same, a water circulating system for said tables and spreading roller, and a heating system for heating the water passing through said tables and spreading roller.

7. A system for casting and annealing plate glass comprising a stationary table, a movable compressing table, a spreading roller carried by said movable table for spreading molten glass upon the stationary table while the movable table is moved above the stationary table, means for permitting said movable table to rest upon the stationary table after said spreading roller has passed beyond the stationary table to compress the molten glass and expel air from the same, a water circulating system for said tables and roller, and electric conductors passing through said table to heat the water and tables while the glass is being rolled.

8. An annealing table comprising a stationary table, a movable table, means for movably mounting said movable table for bringing the same in superposed relation with respect to said stationary table, means for spreading material upon said stationary table, means for moving said movable table into compressing relation to said stationary table, cooling means for said tables, and heating means for said tables.

9. A machine of the character described comprising a stationary table, a movable table, said tables being positioned in superposed relation when said tables are in an operative position, means carried by one of said tables for spreading material upon the other of said tables, means for bringing said movable table into a position to compress material between said tables, cooling means for said tables, and heating means for said tables.

10. A machine of the character described comprising a support, a stationary table, a movable table carried by said support, said tables being positioned in superposed relation when in an operative position, said support being provided with means for permitting said movable table to move vertically into compressing relation to said stationary table when in an operative position, means for cooling said tables, and means for heating said tables.

11. A machine of the character described comprising a stationary compressing element, a movably mounted compressing element, said compressing elements being positioned in superposed relation when in an operative position, means for permitting said movable compressing element to move vertically with respect to said stationary compressing element when said elements are in an operative position, heating means for said compressing elements, and cooling means for said compressing elements.

12. A machine of the character described comprising a stationary compressing element, a movable compressing element, means for movably mounting said movable compressing element to permit the same to travel parallel to said stationary element and move into compressing relation thereto when in an operative position, heating means for said compressing elements, and means for gradually cooling said heating element.

In testimony whereof I affix my signature in presence of two witnesses.

CHARLES R. HAZEL.
